UNITED STATES PATENT OFFICE.

CHARLES R. ABBOTT, OF LOS ANGELES, CALIFORNIA.

MARBLE-POLISHING BUFFER.

Application filed November 24, 1924. Serial No. 751,864.

This invention relates to the art of polishing marble, and more particularly to a novel marble polishing buffer used in this art.

The surface of marble is usually highly polished so that it will have certain reflective qualities which will render it attractive. The marble is first cut into slabs of the desired size and shape. The surfaces to be polished are then ground with a coarse abrasive such as carborundum, and then with a comparatively fine abrasive. The surface is then honed, thus giving it a fair degree of smoothness. The surface treated this far has a minute projections extending therefrom, which are very close together. To acquire the desired polish, these projections must be removed. A marble polishing buffer is used for removing these minute projections. The treated surface is covered with a layer of polishing powder which in most instances is a grain acid and dry, ground putty mixture. The polishing buffer is then pressurably applied to the surface of the marble, this buffer being revolved at a high rate of speed. Water is supplied to the surface through the buffer, this water combining with the polishing powder, forming a paste. The polishing buffer thus employed serves to remove the minute projections, and leaves the surface with a lustrous polish. The rapidity with which the buffer rotates causes the polishing powder to rapidly wear away the buffer, and frequent replacing is necessary. The present type of buffer is made of felt and is very expensive.

It is an object of this invention to provide a buffer having a comparatively long life. My invention employs a polishing element which is comparatively thick and provides an extensive wearing area.

It is another object of the invention to provide a means for supporting the polishing element so that pressure may be applied thereto when the buffer is used for polishing. To accomplish this, I provide a housing having a depending peripheral skirt which extends around the polishing element, and terminates adjacent to the contacting face thereof. As the polishing element wears, the housing is shortened.

It is a further object of the invention to provide a buffer in which the polishing element is securely clamped in place. The polishing element provided by my invention is composed of a multiplicity of lengths of hemp rope placed in parallel relationship in-

side a housing. After these ropes are placed inside the housing, they are saturated with a liquid causing them to swell or expand. The expansion is constricted by the housing 60 and the hemp members are pressurably retained in place by the housing, thus providing a relatively firm buffering element capable of withstanding applied pressure without appreciable distortion and having a buffering 65 surface of relatively soft texture.

Other objects and advantages of the invention will be made evident hereinafter.

Referring to the drawings which are for illustrative purposes only, 70

Fig. 1 is a diagrammatic view illustrating the utility of my invention.

Fig. 2 is an enlarged elevational view of a marble polishing buffer having the features of my invention. 75

Fig. 3 is a plan view of Fig. 2.

Fig. 4 is a section taken on the line 4—4 of Fig. 3.

As shown in Fig. 1, a buffer 11 of my invention is adapted to be used in conjunction with a marble polishing machine which provides a rotating spindle 12. The rotating spindle 12 is rotated by a belt 13 which is driven from a countershaft 14, the countershaft 14 in turn being driven by a belt 80 15. The belt 15 is driven by a shaft 16 which is supported by a column 17. A motor 18 is mounted at the upper end of the column 17 and has a gear 19 which engages and drives a gear 20 for rotating the shaft 85 16. The countershaft 14 is supported at the outer end of a vertically movable frame 22 and the spindle 12 is supported by a radius arm 23. The frame 22 is raised or lowered on the column 17 by actuating a 90 lever 24 which operates a clutch 25, this clutch 25 driving a shaft 26 which rotates a nut 27 on a lead screw 28 by engagement of bevel gears 30. A pressure is applied to the buffer by means of a lever 31 associated with the spindle 12, this lever 31 also serving as a medium through which the buffer 12 is moved over the surface 33 of a slab of marble 34. 95

As clearly shown in Figs. 2, 3 and 4 of 100 the drawings, the lower end of the spindle 12 is reduced at 35 and has keys 36 which extend into key slots 37 of a hub 38 of a mounting head 39, the reduced portion 35 of the spindle 12 extending into a central opening 41 in the hub 38. A web 42 of the mounting head 39 extends radially from the 110

hub 38 and has a peripheral rim 43. Engaging the outer face 44 of the peripheral rim 43 is a housing or depending skirt 45 which converges outwardly from the head 39 or is slightly conical as is evident from Figs. 2 and 4 of the drawing, the housing 45 being smaller in diameter at the lower edge 46 thereof. The housing 45 is secured to the mounting head 39 by cap screws 47. Inside the housing 45 is a polishing element 48. In this modification of my invention I employ a polishing element which is composed of a multiplicity of members in the form of lengths of hemp rope 49. These ropes 49 are arranged inside the housing 45 and extend in parallel relationship with each other. The upper ends of the hemp rope members 49 are adhesively attached to the lower face of the web 42 by any glue substance such as asphaltum. A concentric opening 50 is provided through the bottom of the hub 38 and a hose 52 is extended therethrough. This hose is made of a material which will wear away as the buffing element wears away, and extends to the lower ends of the ropes 49 to provide a water passage which is supplied with water by an opening 53 through the spindle 12. A hose 54 is connected with the upper end of the spindle by which water is supplied to the opening 53.

A very important consideration of my invention is the manner in which the hemp ropes 49 are firmly retained inside the housing 45. In making the buffer 11, I first secure the housing 45 to the head 39, and then place the hemp ropes 49 and the hose 52 in place. I then remove the head from the housing 45 and pour a layer of asphaltum over the upper ends thereof. I then replace the head 39 and secure it permanently in place. The asphaltum serves not only to glue the ropes 49 together, but also serves to glue them to the lower face of the head 39. I then saturate the hemp ropes with water. This causes them to expand, and owing to the fact that they are constricted by the housing 45, the individual expansion of each of the ropes 49 serves to compress them tightly together. This prevents a pulling of any of the ropes 49 from place. By constructing the housing 45 in conical form so that the smaller end thereof is at the lower end of the polishing member 48, an additional resistance against the removal of the ropes is provided.

As clearly shown in Fig. 2, I provide the housing 45 with a number of series of aligned slots 58, these slots being arranged so that only a small bridge of metal, as indicated at 59, separates the aligned slots. When the buffing element 48 wears, the lower edge 60 of the housing 45 moves toward the surface of the marble. It is another feature of this invention to provide a housing which may

be shortened as the lower contacting face of the polishing element wears away. The provision of series of aligned slots accomplishes this feature. When it is necessary to shorten the housing 45, the bridges of metal 59 between the lowermost series of slots 58 are cut, this being readily done by use of a chisel. A lower band thus separated from the housing 45 is then removed and the element 48 will extend an adequate distance below the remaining portion of the housing. This operation may be conducted through the life of the buffer as the polishing element 48 wears. It will be seen that the lower edge of the housing always extends into the adjacency of the polishing surface of the polishing element 48, and at all times supports it so that the necessary pressure for polishing may be applied by the buffer.

Again referring to Fig. 1, if the surface 33 of the slab of marble 34 has previously been worked upon, and is ready for the final polish, it is covered with a layer of polishing powder, as previously described. The buffer 11 is then set upon the slab 34 and the lower end of the spindle 35 is extended into the opening 41 so that the keys 36 extend into the key slots 37. The spindle is then rotated through the shafting and belting as previously described, and water is supplied to the buffer through the hose 54, the opening 53 in the spindle 12, and through the hose 52 to the surface 33, this water combining with the powder and forming a paste. As the buffer 11 rotates, pressure may be applied by means of the lever arm 31 and the buffer may be moved over the surface 33 by swinging the complete radius arm 23 by means of the lever 31.

My invention includes certain unique features which cooperate and provide a marble polishing buffer which is superior to the present buffers in many respects, and which may be produced at one-third the cost of any of the present buffers. In actual production I produce a buffer of my invention for fifteen dollars, whereas the cost of a buffer which in any way equals my invention would be about fifty dollars. The novel manner in which I retain the hemp members 49 in place is an important feature of my invention. The housing 45 being constructed so that it may be readily shortened also constitutes an important feature of the invention. When the polishing element 48 has worn to the extent that it can no longer be used, the mounting head 39 may be removed from the element 48 and the housing 45, and a new housing and element attached thereto. In other words, the head 39 is practically everlasting, and it is necessary to replace only the wearing parts, namely, the polishing element 48 and the housing or skirt 45.

I claim as my invention:

1. In a buffer, the combination of: a mounting head having a depending peripheral skirt converging from said head outwardly and constituting a housing; and a buffering element consisting of a plurality of longitudinally disposed strands of rope tightly compacted in said housing and extending only slightly beyond the outer edge of said skirt, the ends of said strands of rope forming a relatively firm buffering element capable of withstanding applied pressure without appreciable distortion and having a buffering surface of relatively soft texture, there being a fluid passage through said head and buffering element, said skirt being perforated to facilitate the removal of portions thereof as said strands of rope are worn away.
2. In a buffer, the combination of: a mounting head having a depending peripheral skirt converging from said head out-

In testimony whereof, I have hereunto set my hand at Los Angeles, California, this 15th day of November 1924.

CHARLES R. ABBOTT.
